DESIGN FOR A HANDLE FOR SAWS OR LIKE ARTICLES

Wilbur P. Peterson, Kansas City, Mo.

Application November 6, 1944, Serial No. 116,189

Term of patent 14 years

(CL. D93—4)

To all whom it may concern:

Be it known that I, Wilbur P. Peterson, a citizen of the United States, residing at Kansas City, in the county of Jackson and State of Missouri, have invented a new, original, and ornamental Design for a Handle for Saws or Like Articles, of which the following is the specification, reference being had to the accompanying drawing, forming part thereof.

Fig. 1 is a side view of a handle for saws or like articles, showing my new design;

Fig. 2 is a perspective view; and

Fig. 3 is an end view thereof.

I claim:

The ornamental design for a handle for saws or like articles, substantially as shown.

WILBUR P. PETERSON.
